His Attorney

UNITED STATES PATENT OFFICE.

WILLIAM G. SEMPLE, OF CINCINNATI, OHIO.

CAR-HEATER.

SPECIFICATION forming part of Letters Patent No. 246,223, dated August 23, 1881.

Application filed May 20, 1881. (No model.)

To all whom it may concern:

Be it known that I, WILLIAM G. SEMPLE, a citizen of the United States, residing at Cincinnati, Hamilton county, Ohio, have invented 5 new and useful Improvements in Car-Heaters, of which the following is a specification.

My invention relates to heaters for railway-cars, its object being to provide an efficient, practicable, and economical device for this 10 purpose, adapted more especially for street-railway cars.

To this end my invention consists in the construction of the heating apparatus, and in the arrangement of the same in relation to the car, 15 all as hereinafter more fully and at large set forth.

My invention, as adapted to a street-railway car, is illustrated in the accompanying drawings, in which—

20 Figure 1 is a vertical longitudinal section of the entire apparatus. Fig. 2 is a plan view of the same. Fig. 3 is a cross-sectional elevation of the same as viewed from the front. Fig. 4 is a partial cross-section, showing the 25 air-admitting device in elevation; and Fig. 5 is a detached plan view of the air-admitting device.

Similar letters of reference indicate similar parts in both specification and drawings.

30 In the embodiment of my invention shown in the drawings the apparatus is suspended beneath the front platform, B, of the car, between the central and side sills, from a perforated foot-plate, G, which forms a standing-place 35 for the driver, and is laid upon the sills, part of the flooring being removed for that purpose.

The apparatus consists, substantially, of a 40 double-walled air-chamber, A, containing a stove or fire-pot, C, and provided with apertures for the admission of the air from without, and terminates at the rear in a flue, L, by which the air is conveyed to a register, M, in the floor of the car and there discharged.

45 The apparatus rests upon a horizontal plate, D, of rectangular form, which is the bottom of the air-chamber, and is also the support for the fire-pot. The side walls, F F', of the air-chamber are of sheet-iron, secured between the

bottom plate, D, and an upper plate, D', said 50 plates having low flanges on their corresponding surfaces, which are interposed between and keep the walls F F' in proper position. The wall is doubled for the purpose, as will be readily understood, of obtaining a surrounding 55 space for air or other non-conductor of heat, to prevent loss by radiation, and the double wall is continued into and forms the air-conducting flue L, for the same purpose. The upper plate, D', is cast with flanges projecting 60 upwardly around its edges, making a trough, which is filled with plaster-of-paris or other non-conducting filling, f, and is inclined upwardly from front to rear at such an angle as will facilitate the passage of the heated air 65 from the air-chamber toward and into the conducting-flue L.

The entire apparatus is suspended by bolts 70 a', extending downward from the foot-plate G through the plates D' and D, within the side walls, F F', and by means of sleeves a' interposed between the upper plate, D', and the foot-plate G, and nuts at the lower ends of the suspending-bolts the parts are securely fastened together and suspended from the foot- 75 plate.

The stove or furnace part of the apparatus consists of an open-ended fire-pot, C, of rectangular horizontal section, with rounded corners, which rests in a suitably-formed recess 80 or within a flange of the bottom plate, D, and surrounds an opening in the bottom plate, across which the tilting grate c is hung, the pivot of which extends rearward, and is provided with a suitably-formed arm, engaging a 85 hook or other suitable fastening, for holding it in position, yet allow it to be tilted and the fire-pot discharged when necessary. The fire-pot C is higher at the rear than in front, thus giving its top plate, E, an inclination upward 90 at the rear—a construction which facilitates the heating and passage of air above it, and also the passage of the gases of combustion to the exit p at the rear within the fire-pot. The plate E is provided with an aperture extended 95 upward into a throat or channel by a flange, E', passing through the upper plate, D', and is further provided with a removable double-

walled cover, *g*, fitting closely the mouth. Directly above this, in the foot-plate *G*, is a corresponding opening, also fitted with a removable cover. Through these openings coal is fed through the throat *E'* into the fire-pot.

The provision for admitting air into the chamber surrounding the fire-pot is as follows: The bottom plate, *D*, is provided with a line of perforations, *d*, around the fire-pot and within the side walls. In addition to these the air-chamber is provided laterally on each side, near the front, with an opening, *d'*, through the side walls, elongated vertically. These latter openings have each a double-flanged mouth-piece, *r*, opening to the front and rear, as shown in Figs. 2, 4, and 5, with which an automatic swinging gate, *s*, is connected, so as to guide the current of air from either direction into the openings, and thus utilize the movement of the car in either direction for obtaining a forced current of air into the heating-chamber. The smoke-pipe *p* is extended from the fire-pot *C* rearward horizontally within the flue *L* a short distance, and thence is carried without the same laterally to a point below the corner of the car, where it is connected with a vertical pipe, *p'*, extending up through the body of the car and discharging over the roof. This discharge can also be made at the rear end of the car by carrying an ordinary smoke-pipe under the seat of the car.

The pipe *p'* is surrounded by a suitable casing as a protection for surrounding objects against the heat.

I protect the front of the heater and the air-openings from becoming obstructed by dirt by suspending a wire screen, *t*, vertically in front of the same, beneath the car.

The perforations in the foot-plate *G* allow the heat to rise through and warm the plate sufficiently to make it a comfortable standing-place in cold weather.

It will be observed that the entire heating apparatus is suspended upon and held together by the bolts *a'*, and that it is therefore readily

taken apart for repairs, or removed from the car when not in use, by removing the nuts below.

Having described my invention, I claim and desire to secure by Letters Patent—

1. In a railway-car-heating apparatus, in combination with the inclosed stove or heater proper, the air-chamber *A*, constructed as described and shown, consisting of the bottom plate, *D*, top plate, *D'*, and side walls, *F F'*, held between the upper and lower plates, and the suspending-bolts *a'*, extending through the air-chamber and sustaining the bottom plate, which supports the fire-pot *C*, substantially as specified. 55

2. The combination of the plates *D* and *D'*, side walls, *F F'*, suspending-bolts *a'*, and thimbles *a''* with the inclosed heater and the rear air-conducting flue, *L*, substantially as specified. 60

3. The combination of the fire-pot *C*, top plate, *E*, having the feeding-throat *E'*, removable cover *g*, surrounding air-chamber *A*, side walls, *F F'*, top and bottom plates, *D D'*, and bolts *a'*, extending through the air-chamber 70 and sustaining the bottom plate, *D*, which supports the fire-pot, substantially as described.

4. In combination with the fire-pot *C*, having the inclined top plate, *E*, casings *F F'* and *D'*, and rear conducting-flue, *L*, the ingress-openings *d* and *d'*, arranged as shown, the latter openings being provided with funnel-mouths, substantially as and for the purposes set forth. 75

5. In combination with a street-car provided with a heater arranged beneath the forward platform, the screen *t*, substantially as and for the purpose specified. 80

In testimony whereof I have hereunto set my hand in the presence of two subscribing witnesses.

WILLIAM G. SEMPLE.
